G. F. HIPP AND J. B. FAST, OF NOVA, OHIO.

Letters Patent No. 68,508, dated September 3, 1867.

IMPROVEMENT IN HAY-ELEVATOR.

The Schedule referred to in these Letters Patent and making part of the same.

TO ALL WHOM IT MAY CONCERN:

Be it known that we, G. F. HIPP and J. B. FAST, of Nova, in the county of Ashland, and State of Ohio, have invented a new and useful Improvement in Hay-Elevators; and we do hereby declare that the following is a full, clear, and exact description thereof, which will enable others skilled in the art to make and use the same, reference being had to the accompanying drawings, forming part of this specification, in which—

Figure 1 is a vertical section of our improved machine taken through the line $x x$, fig. 2.

Figure 2 is a top or plan view of the same.

Similar letters of reference indicate like parts.

Our invention has for its object to furnish an improved machine for operating a hay-fork or elevator more conveniently and satisfactorily; and it consists in the wheel and sweep constructed, arranged, and operated substantially as hereinafter more fully described.

The dimensions of the various parts given in the following description are to be taken as merely suggested, the absolute dimensions depending upon the circumstances of each case and the work the machine is required to do.

A are the sills, which cross each other at right angles at the centre, where they are notched together, as shown in the drawings. The sills A are eight inches broad, five inches thick, and of sufficient length to give stability to the machine. B is the post to which the wheel is pivoted, which is four inches in diameter, passes through a mortise in the sills A, and extends beneath them about ten inches, being strengthened and firmly secured in place by the braces C, attached to its lower end and to the lower sides of the sills A. D is the wheel, which is six feet in diameter. The sides of the wheel D are made of timbers, d' , one and a half inch thick, and which are eight inches wide at the centre, tapering to four inches wide at the ends. Two of the timbers d' cross and are notched into each other at the centre, and the others are fitted into the angles formed by their intersection. The centres of the sides D are strengthened by planks E, one and a half inch thick and twenty inches square, firmly bolted to said sides, as shown in figs. 1 and 2. The sides D are placed one foot apart, and they are connected to each other and kept in their proper relative positions by the timbers F, which are two and a half inches square, and are mortised into the arms d' of the sides D, near their ends, as shown in the drawings. The ends of the contiguous arms d' of each side are connected to each other by the braces G, which are four inches broad, one inch thick, and of sufficient length to reach from arm to arm of the sides D. H are hooks attached to the lower sides of the ends of the arms d' of the lower side D, to prevent the rope I from dropping from the wheel when slackened. J is the sweep, which has a hole through it about three inches in diameter, through which passes the upper end of the post B. K is an iron brace, the ends of which are attached to the sweep J, and its middle part is pivoted to the top of the post B by a screw-bolt passing through the said brace and screwing into the top of the said post. L is a clutch or hook pivoted to one side of the sweep J in such a position that when dropped down it will catch upon one or the other of the arms d' of the upper side of the wheel, and carry the said wheel with it to raise the fork and hay; but when turned up the sweep and wheel will each revolve independently of the other, so that the fork can be drawn back and the rope, I, unwound from the wheel without backing the horse. I is the rope which is attached to the rim of the wheel, and passes thence over the necessary guide-pulleys to the hay-fork.

What we claim as new, and desire to secure by Letters Patent, is—

The wheel D and sweep J, in combination with each other, when said wheel and sweep are constructed, arranged, and operated substantially as herein shown and described; and for the purpose set forth.

G. F. HIPP,
J. B. FAST.
